UNITED STATES PATENT OFFICE.

FRANK WOODWARD CANN, OF BROOKLYN, NEW YORK.

MACHINE FOR BEVELING THE EDGES OF ELECTROTYPE OR STEREOGRAPHIC PRINTING-PLATES.

SPECIFICATION forming part of Letters Patent No. 785,349, dated March 21, 1905.

Application filed December 30, 1903. Serial No. 187,116.

To all whom it may concern:

Be it known that I, FRANK WOODWARD CANN, a citizen of the United States, and a resident of Brooklyn, county of Kings, and 5 State of New York, have invented certain new and useful Improvements in Machines for Beveling the Edges of Electrotype or Stereotype Printing-Plates, of which the following is a specification, reference being had to the 10 accompanying drawings, forming a part thereof, in which similar letters of reference indicate corresponding parts.

The subject of this invention is a machine for beveling the edges of electrotype or stereotype printing-plates, especially plates of segmental transverse contour adapted for use in connection with the printing-cylinders of a cylinder printing-press, and has for its more prominent objects convenience and facility 20 for adjusting the plates for application to the cutters, capacity for accurately beveling the plates on all four sides, notwithstanding the fact that the plates may be in the form of curved segments, and also capacity for varying 25 the pitch of the bevel formation of the edges.

With the above and other purposes in view the novel machine comprises a peculiarly-conditioned saddle or clamp by which a segmental plate may be readily and rigidly secured in a manner to present either one of its straight transverse or curved longitudinal edges to a suitable cutter for acquiring the proper bevel, the saddle being capable of 30 quickly permitting said plate to be detached and clamped in a reversed position, so that the corresponding opposite edge can be similarly operated upon, novel means being provided whereby the clamped plate in any of its 35 several adjustments can be fed with positiveness and uniformity to an appropriate beveling device to attain the desired bevel.

There are other important features connected with the invention, which in addition 40 to those alluded to are clearly set forth in the subsequent detailed description.

In the accompanying drawings, forming part of this specification, Figure 1 is a plan view of a beveling-machine embodying my 45 invention. Fig. 2 is an end elevation of said

machine looking in the direction of the arrow x , Fig. 1. Fig. 3 is an end view of the clamping-saddle and part of its shaft or guide-rod. Fig. 4 is a side view of said saddle and shaft. Fig. 5 is a detail view of one 55 of the disks connected with the means for adjusting the position of the plate-clamping saddle.

The main or supporting frame of the machine may be of any desired construction and 60 arrangement. I have shown the same as comprising a base A, rigidly on which are the corner standards A', connected together at their upper ends by the side and transverse bars A² A³. In bearings a a, centrally located on the bars A³, revolves a horizontal shaft B, on the projecting ends of which immediately contiguous to said bars A³ are mounted the relatively reversed beveling-cutters B' B², each of which is equipped at its 65 inner side with a circular saw b² b³. Keyed on the shaft B is a small pulley c, which is driven by being geared by a belt C, with a larger pulley c' on the shaft C', turning in suitable bearings on the base and having a driving-pulley c² belted with the source of power. 70

Stepped in bearings on the base A and also revolvably supported by bearings in the side bars A² of the frame, at intermediate points thereof, are vertical shafts D, the upper extremities of which project for a short distance above said side bars and have secured thereon horizontal beveled pinions d in mesh with beveled pinions d', keyed on a transverse shaft D', mounted in suitable brackets 85 D², secured on said side bars. It will be observed by reference to Figs. 1 and 2 that the gears d' are correspondingly disposed with reference to their companions so that upon revolving the shaft D' by means of a hand-crank d² both shafts D D will be revolved in the same direction and at the same rate of speed. The upper portions of the shafts D are threaded, as indicated at d³, and surrounding the same and in threaded engagement therewith are bearings E, formed integral with the side bars G² G³, which form part of a vertically-movable carriage. This carriage further embodies transverse bars G³ G³, 90 said bars having end extensions g, in which 95 100

are slidably mounted guide-rods F, which, in effect, establish connection between the said bars at each end. A shaft G, supported at its rounded ends g' in bearings l, secured, respectively, at one end of each of said rods F, is square in cross-section. On this said shaft G is mounted a carrier H, consisting of two relatively reversed angular sections h h', having oppositely-located ears h² in mutual contact and perforated for the reception of screws or bolts h³, by which said sections are slidably confined on the bar. A saddle H' has a lower recessed portion adapted to be fitted upon the upper section h and rigidly secured in position through the medium of a bolt h⁴. This saddle has an upper rest h⁵, which is curved in one direction and of such ample capacity as to adapt it for having placed thereon a curved electrotype-plate H², which is rigidly secured upon such bed by means of suitable clamps H³. A somewhat similar guide H⁴ and saddle H⁵ are provided for the opposite side of the apparatus, the guide, however, in this instance being mounted on a longitudinally-disposed stub-shaft H⁶, which is square in cross-section, but has a cylindrical portion bearing in an opening in the bar G', so that said shaft may be turned relative to said bar. Secured to the shaft H⁶ is a toothed pinion or gear-segment h⁷, meshing with a worm h⁸, revolving with a shaft H⁷, turning in hangers h⁹, carried by the bar G³, one of the ends of said shaft being projecting and having a small hand-crank h¹⁰, by which said shaft can be conveniently rotated.

The shaft G is revolvably supported at its ends, so that same may be turned to vary the angle of the position of the guide and saddle thereon. Secured to one of the end bearings of said shaft is a disk I, through which the cylindrical end of the shaft extends, and carries on its projecting portion a coincidentally-located disk I', having an arc-shaped slot i, adapted to register with a threaded perforation in the disk I. A shouldered and handled clamping-bolt I² is adapted to have its threaded portion inserted through the slot and engage the threaded perforation in the disk I, so that the said disks may be firmly clamped together. Obviously by loosening the bolt I² the disk I' may be turned to correspondingly affect the shaft G and the latter retained in such adjusted position by the tightening of the bolt I², as explained.

Mounted in bearings j at the ends of the extensions g of the bars G³ are longitudinal feed-shafts J, having intermediately-threaded portions j', engaging the threaded heads k of arms K, rigidly secured to and projecting from the rods F.

It may be well to here state that, as will be readily recalled by those familiar with this art, the curved electrotype-plates are fitted upon the cylinders of the press by beveled transverse edges of the plates being engaged

beneath dovetailed ribs or connections transversely on said cylinders. This requires that the plates shall have such transverse edges appropriately beveled, as well as trimmed, and it is also desirable that their side edges 70 should be correspondingly conditioned. In the latter case the beveling and trimming are to prepare said side edges to fit beneath dovetailed ribs circumferentially on the cylinder. It will therefore be appreciated that 75 such beveling and trimming operations should be conducted with accuracy and that economy and despatch require that said operations should also be quickly and conveniently effected. My machine has the considerations 80 stated in view.

It will be readily comprehended from the foregoing that by clamping one of the plates upon the saddle H' the shaft G may be turned and held in its bearings so that when the inner straight edge of the plate is presented to the cutter it will receive the appropriate bevel. The adjusted plate is moved horizontally and brought in line with the cutting-path of said cutter by operating the hand-crank j² on the ends of the feed-shafts J, so that the bar G, through the several connections, will be moved inward or outward relative to the cutter, according to the direction in which the shafts J are revolved. To effect 95 the proper vertical adjustment of the plates, rotary movement in either required direction is given the shaft D' through the medium of the hand-crank d². With the carrier H, its saddle, plate thereon, and the bar G conditioned as described, the carrier, together with the saddle and plate, may be shifted along said bar, so that the cutter will bevel the contiguous side edge of the plate and the saw b² trim the same. At the termination 100 of this operation the saddle H' and plate may be quickly removed from the guide and adjusted in a reverse position, with the opposite side edge of the plate in position for contact with the cutter, whereupon the remaining straight edge of the plate can be similarly beveled and trimmed. For the purpose of beveling and trimming the curved ends of said plate the latter is now transferred to the saddle H⁵ at the opposite side 105 of the machine and secured in position the same as in the case of the other saddle, excepting that the clamps are placed over the side edges instead of at the curved ends. It 110 will be necessary in beveling and trimming 115 the curved ends to turn the plate so that each part of the edge to be acted upon by the cutter B² comes in direct contact. This is effected by turning the shaft H⁶, which through the medium of the worm-gear transversely tilts the saddle in one direction or the other, as may be desired. Manifestly by removing and readjusting the plate in reversed relation the opposite curved edge can be similarly beveled and trimmed. 120 125 130

It will be appreciated that the improved machine is not only comparatively simple, but it is susceptible of accurately and expeditiously beveling and trimming the plates 5 at all four edges thereof and that the degree or pitch of bevel may be readily varied according to requirement.

I do not desire to be understood as limiting myself to the particular construction and 10 arrangement of parts shown and described, but reserve the right to all modifications that may be fairly within the scope of my invention.

Having now described my invention, what 15 I claim as new, and desire to secure by Letters Patent, is—

1. In a machine of the character described, the combination with a revoluble bevel-cutter, of a shaft in juxtaposition thereto and 20 revolubly supported in suitable bearings, means for adjustably holding said shaft against turning in said bearing, a carrier supported by the shaft and having a saddle, together with clamping devices for securing a 25 plate on said saddle, the carrier being longitudinally movable relative to said shaft.

2. In a machine of the character described, the combination with a supporting-frame, a shaft revolubly mounted in said frame, and a 30 head comprising a bevel-cutter and a circular saw mounted thereon, of another shaft in juxtaposition thereto, revolubly supported in bearings on said frame, means for adjustably holding said last-named shaft from 35 turning in its bearings, a carrier longitudinally movable on said last-named shaft, a saddle mounted on said carrier, and a clamp holding a plate on said saddle.

3. In a machine of the character described, 40 the combination with a supporting-frame, a shaft revolubly mounted in said frame and a cutter-head mounted thereon, of another shaft in juxtaposition thereto, revolubly supported in bearings in said frame, means 45 comprising a slotted disk, a disk having a screw-threaded opening, and a set-screw engaging said slot and opening, and adjustably holding said last shaft from turning in its

bearings, a carrier longitudinally movable on said last-named shaft, a saddle mounted 50 on said carrier and a clamp detachably holding a plate on said saddle.

4. In a machine of the character described, the combination with a supporting-frame, a shaft revolubly mounted in said frame, and 55 a cutter-head on said shaft, of another shaft in juxtaposition thereto revolubly supported in bearings on said frame, means for adjustably holding said last-named shaft from turning in its bearings, a carrier comprising 60 two pieces, embracing said last-named shaft, and longitudinally movable thereon, a saddle comprising an upper curved portion, a lower slotted portion, and a set-screw detachably mounted on said carrier, and a clamp detach- 65 ably holding a plate on said saddle.

5. In a machine of the character described the combination with a revoluble shaft and supporting-frame therefor, cutter-head on said shaft, said head embodying a bevel- 70 cutter and circular saw, of a rotatable shaft in juxtaposition thereto, means for rotating and adjustably holding said last-named shaft, comprising a crank, a worm and worm-wheel, and a carrier and saddle longitudinally 75 slidable on said last-named shaft, and clamps for detachably holding an electro-type on said saddle.

6. In a machine of the character described the combination with a revoluble bevel- 80 cutter, of a vertically-adjustable and rotatable shaft in juxtaposition thereto, and means for adjusting said shaft and for adjustably holding it in its bearings, a carrier supported by the said shaft and having a saddle, together 85 with clamping devices for securing a plate on said saddle, the carrier being longitudinally movable on the shaft.

In testimony that I claim the foregoing as my invention I have signed my name, in 90 presence of two witnesses, this 21st day of December, 1903.

FRANK WOODWARD CANN.
